ATTORNEY.

UNITED STATES PATENT OFFICE

ELMER C. MORRIS, OF CHICAGO, ILLINOIS, ASSIGNOR, BY MESNE ASSIGNMENTS, TO
SERVO PAPER CORPORATION, A CORPORATION OF ILLINOIS
DISPENSING DEVICE FOR FOLDED NAPKINS AND THE LIKE

Original application filed June 7, 1924, Serial No. 718,419. Divided and this application filed July 19, 1928. Serial No. 293,964.

This invention relates to improvements in dispensing devices of that type in which a closed container is provided for holding folded paper napkins, or like articles, to protect them against soiling previous to use and to permit the withdrawal of but a single article at the same time to prevent waste of the articles.

One of the objects of the invention is to provide a container comprising a casing divided transversely at an intermediate part into two complementary sections, which are hinged together so that the casing can be easily opened and closed for loading the same; the two sections are adapted to form opposite receptacles to receive respectively stacks of the articles, with the two stacks separated by an intervening space, in which is mounted a spring mechanism adapted to press the stacks toward the end walls of their respective sections so that individual articles can be dispensed through openings in the end walls of the sections when the two sections are closed. Another object of the invention is to provide means whereby the spring mechanism is automatically displaced when the casing is opened for reloading, so that the spring mechanism will not interfere with the introduction of the new stacks of articles.

This application is a division of my former application for improvements in dispensing devices filed June 7, 1924, bearing Serial No. 718,419, in which the instant invention is disclosed as a modification of the device therein shown and described.

The instant invention is described in detail hereinafter, pointed out in the appended claims, and illustrated by the accompanying drawings.

In the accompanying drawings, in which similar reference characters designate corresponding parts.

Figure 1 is a vertical sectional view of a dispensing device embodying the invention, showing the container opened and the spring mechanism displaced therefrom.

Figure 2 is a similar view, with the casing closed.

Figure 3 is a plan view of the interior of

the casing with the top removed, the walls being shown in section.

Referring to the drawings in detail, 10 designates a supporting standard for the device, formed of stout wire bent to form legs 55 11 (any two of which are shown) quadrilaterally positioned with relation to each other and a seat 12 slightly ridged toward its transverse middle part. Extending downward from the under side of the seat 60 are the parallel members 13 forming a vertical guide-way, the purpose of which will be explained further on.

The container for the articles to be dispensed, comprises a casing of a generally 65 cubical shape, somewhat elongated in one direction, and with its side and end walls slightly declined inward. This casing is transversely divided midway between its ends to form two complementary sections 14 70 and 15, respectively, in the end walls of which opposite dispensing openings 16 are formed.

The top and bottom of the casing are slightly ridged toward the meeting edges of 75 the complementary sections, the bottom fitting the seat 12 of the supporting standard. The mutual engagement between the seat and bottom of the casing tends to hold the casing on the standard against accidental 80 displacement. The meeting edges of the bottoms of the two complementary sections 14 and 15 are hinged together by the pintle 17. On the top of one of the sections is fixed the catch 18 adapted to engage a depression 85 in the top of the other section to hold the two sections together when the casing is closed.

Mounted in the casing is a spring means for feeding the stacked articles in the respective sections toward the end walls and over the dispensing openings in said walls. In the central part of the casing is mounted the plate 19 transversely of the casing and extending at its lower part between the adjacent bottom edges of the complementary sections. The plate is hinged to the bottom edges by the pintle 17 that also hinges together the two bottom parts. With the casing properly positioned on the seat 12 of 100

the supporting standard, the plate 19, at its lower part, is slideable in the vertical guide-way formed by the members 13 of the supporting standard. This engagement of 5 the plate with the guide-way imposes a vertical movement on the plate with relation to the standard when the plate is moved in the guide-way.

Straddling the upper edge of the plate 19 10 is a spring 20 of resilient strip metal, folded over the edge of the plate and clamped thereto by the bolt 21. The spring comprises the arms 22 normally diverging outwardly from opposite sides of the plate as shown 15 in Fig. 1. The arms carry at their extremities the presser-feet 23 extending upwardly and inwardly toward the plates, when the spring is in its normal condition, as shown in Fig. 1.

20 The spring, as a whole in its normally extended condition, covers a distance somewhat greater than the length of the casing when the latter is closed and the length of each presser-foot is slightly less than the 25 length of the dispensing opening in the opposite end wall of the casing.

In dispensing the napkins, the parts of the device are positioned as indicated in Fig. 2, with the complementary casing sections 30 14, 15 closed, each of the sections having been loaded with a stack of the articles. Preliminary to stacking, each of the napkins 24, which may have been folded into a plurality of plies, is folded to provide comparatively long and short folds. In stacking, the napkins are arranged with their short 35 folds extending in uniform sequence on the same side of the pack and the shorter folds on the same face of the longer folds. A 40 stack so formed is positioned in each of the casing sections with the napkins on edge and that part of the stack containing the shorter folds lowermost. The stack is positioned in the casing section to abut the end 45 wall thereof with the short fold of the outside napkin registering with the dispensing opening 16 in said wall.

In the space between the stacks is located 50 the spring 20, compressed therebetween with the presser-feet 23 bearing against the inner sides of the stacks to press the latter toward the end walls of the complementary casing sections respectively containing the stacks. The marginal flange of the end 55 wall engages the stack and holds the same against the action of the presser-foot, but the pressure of the latter tends to bulge the stack through the dispensing opening 16. This bulging effect tends to project the free 60 end of the shorter fold of the front napkin through the dispensing opening so that it can be readily grasped and the napkin withdrawn through the opening. As the articles are withdrawn, the stack is fed forward 65 against the end wall. Owing to the con-

siderable length of each presser-foot and its supporting arm and the resilient nature of the metal strip forming the spring, a fairly uniform pressure is maintained against the stack and this pressure is not great enough 70 to interfere with an easy withdrawal of the napkins. To prevent injury to the napkins by contact of the presser-foot, a follower 75 may be interposed between the presser-foot and the stack.

To reload the container, the catch 18 is released and the complementary casing sections 14, 15 are opened, as shown in Fig. 1, to rest on the supporting standard with the dispensing faces of the casing downward. When the sections are turned as indicated, they move clear of the spring 20—23 and the plate 19 slides upwardly in the 80 guide-way formed by the members 13 of the supporting standard. The plate so moved supports the spring above the opened sections so that new stacks can be easily loaded into the sections and the follower plates positioned on the stacks. The complementary sections of the casing are then closed over 85 the spring, compressing the latter between the stacks, which are urged toward the dispensing faces of the casing. With the sections closed, the catch 18 springs into place 90 to hold the sections closed.

What I claim is:

1. A dispensing container for folded napkins and the like, comprising a casing transversely divided at an intermediate part into two complementary sections, each section having a dispensing opening in its end wall, means for hinging together the two sections whereby they may be closed in complementary relation, said sections being adapted to receive stacked articles to abut the said end walls of the respective sections to be dispensed through the openings therein, and with the stacks spaced apart to provide a recess therebetween coincident with the meeting parts of the sections, and spring means mounted in the casing within said recess to be compressed between the stacks when the sections are closed, the compressed spring means operating to urge the opposite stacks toward the end walls of the respective sections.

2. A dispensing container for folded napkins and the like, comprising a casing transversely divided into two complementary sections, each section having a dispensing opening in its end wall and adapted to receive a stack of napkins to abut the end wall of the section to be dispensed through the opening in said wall, spring means in the casing operative on closing of the casing sections to urge the opposite stacks toward the end walls of the respective sections containing said stacks, a hinge connection between the bottoms of the complementary casing sections including a pintle, and a

mounting for the spring means in the casing including said pintle.

3. A dispensing container for folded napkins and the like, comprising a casing transversely divided into two complementary sections, each section having a dispensing opening in its end wall and adapted to receive a stack of napkins to abut the end wall of the section to be dispensed through the opening in said wall, spring means in the casing operative on closing of the casing sections to urge the opposite stacks toward the end walls of the respective sections containing said stacks, a hinge connection between the bottoms of the complementary casing sections including a pintle, and a mounting for the spring means in the casing including said pintle.

4. A dispensing container for folded napkins and the like, comprising a casing transversely divided at an intermediate part into two complementary sections, each section having a dispensing opening in its end wall and adapted to receive a stack of napkins to abut the end wall of the section, hinge means including a pintle connecting the adjacent edges of the bottoms of the complementary sections, means for holding the complementary sections in closed relation, spring means positioned in an intermediate part of the casing to be compressed between opposite contained stacks when the sections are closed, said spring means under compression operating to press the contained stacks toward the end walls of the respective complementary casing sections, and a mounting including the pintle for holding the spring means in place.

5. A dispensing container for folded napkins and the like, comprising a casing transversely divided at an intermediate part into two complementary sections, each section having a dispensing opening in its end wall and adapted to receive a stack of napkins to abut the end wall of the sections, hinge means including a pintle connecting the adjacent edges of the bottoms of the complementary sections, means for holding the complementary sections in closed relation, and spring means mounted in the casing and connected with the pintle to be held in place thereby, said spring means being positioned in an intermediate part of the casing to be compressed between opposite contained stacks when the casing sections are closed, said spring means under compression operating to press the container stacks toward the end walls of the respective complementary casing sections.

6. A dispensing container for folded napkins and the like, comprising a casing transversely divided into two complementary sections, each section having a dispensing opening in its end wall and adapted to receive a stack of napkins to abut the end wall of

the section to be dispensed through the opening in said wall, hinge means connecting the bottoms of the complementary casing sections, opposite presser-feet operative to engage respectively the opposite stacks of napkins, a mounting for the presser-feet including spring arms respectively attached at an end to the opposite presser-feet, and common means connecting the other ends of the spring arms to the hinge means to maintain the presser-feet and spring arms in position with relation to the container, said presser-feet and spring arms being compressed between the stacks on closing the casing sections to urge the stacks toward the end walls of the respective casing sections.

7. A dispensing container for folded napkins and the like, comprising a casing transversely divided into two complementary sections, each section having a dispensing opening in its end wall and adapted to receive a stack of napkins to abut the end wall of the section to be dispensed through the opening in said wall, hinge means including a pintle connecting the bottoms of the complementary casing sections, opposite presser-feet operative to engage respectively the opposite stacks of napkins, a mounting for the presser-feet including spring arms respectively attached at one end to the opposite presser-feet, and a common means connecting the other ends of the spring arms to the pintle of the hinge means to maintain the presser-feet and spring arms in position with relation to the container, said presser-feet and spring arms being compressed between the stacks on closing the casing sections to urge the stacks toward the end walls of the respective casing sections.

8. A dispensing container for folded napkins and the like, comprising a casing transversely divided into two complementary sections, each section having a dispensing opening in its end wall and adapted to receive a stack of napkins to abut the end wall of the section to be dispensed through the opening in said wall, spring means in the casing operative on closing of the casing sections to urge the opposite stacks toward the end walls of the respective sections containing said stacks, an element constituting a hinge connection between the bottoms of the complementary casing sections, and a support for the spring means connected with said element to maintain the spring means in operative position with regard to the casing.

9. A dispensing container for folded napkins and the like, comprising a casing transversely divided into two complementary sections, each section having a dispensing opening in its end wall and adapted to receive a stack of napkins to abut the end wall of the section to be dispensed through the opening in said wall, spring means in the casing operative on closing of the casing

- sections to urge the opposite stacks toward the end walls of the respective sections containing said stacks, a hinge connection between the adjacent edges of the bottoms of the casing sections including a pintle, a member connected at an intermediate part with said pintle and carrying at its upper part the spring means to position the same with regard to the casing.
10. The combination with a supporting standard provided with a vertical guideway, of a dispensing container for folded napkins and the like adapted to be seated on said supporting standard, said container comprising a casing transversely divided into two complementary sections, each section having a dispensing opening in its end wall and adapted to receive a stack of napkins to abut the end wall of the section to be dispensed through the opening in said wall, spring means in the casing operative on closing of the casing sections to urge the opposite stacks toward the end walls of the respective sections containing said stacks, a hinge connection between adjacent edges of the bottoms of the casing sections including a pintle, a member extending between the edges of the bottoms of the casing sections and registering at its intermediate part with the vertical guideway of the supporting standard, said member being connected by the pintle to the casing bottoms and carrying at its upper end the spring means, said member sliding in the guideway as the casing sections are opened and closed to maintain the spring means in operative position with relation to the casing.
11. In a dispenser for napkins and the like, the combination with receptacles hingedly connected together at one end and provided with openings for the withdrawal of the contents thereof, of means for adjustably positioning the said contents adjacent the said openings and comprising a supporting member connected with said receptacles adjacent to their hinged connection and spring members mounted at one end on said supporting member within said receptacles and adapted with their free ends to press said napkins toward the said openings, and means for locking together the free ends of the said hinged receptacles.
12. In a dispenser for napkins and the like, the combination with receptacles hingedly connected together at one end and provided with openings for the withdrawal of the contents thereof, a member mounted to extend within the receptacles, and a pair of flat bowed spring arms fastened at one end to said member and adjustably positioning the said contents adjacent the said openings and adapted with their free ends to press the napkins toward said openings.
13. A dispensing container for folded napkins and the like, comprising a casing

including opposed sections providing end walls for the casing with each wall having a central dispensing opening, means for hingedly connecting the sections whereby they may be closed upon separated stacks of napkins arranged in the casing to abut the respective end walls to be dispensed through the openings therein, a pressure-exerting device mounted in the casing to urge the separated stacks toward the respective end walls of the casing sections when closed, and means whereby said device is actuated by the closing action of the filled sections.

In testimony whereof I affix my signature. 80
